UNITED STATES PATENT OFFICE.

JOHN T. AUSTIN AND BASIL G. AUSTIN, OF HARTFORD, CONNECTICUT, ASSIGNORS TO
AUSTIN ORGAN COMPANY, OF HARTFORD, CONNECTICUT, A CORPORATION OF
MAINE.

ELECTRICALLY-GOVERNED KEY-OPERATED MECHANISM.

1,303,626.

Specification of Letters Patent.

Patented May 13, 1919.

Application filed January 11, 1919. Serial No. 270,644.

To all whom it may concern:

Be it known that we, JOHN T. AUSTIN and BASIL G. AUSTIN, citizens of the United States, residing at Hartford, in the county 5 of Hartford and State of Connecticut, have invented certain new and useful Improvements in Electrically-Governed Key-Operated Mechanism, of which the following is a specification.

10 This invention relates to electrically-governed key-operated mechanism such for instance as is used in organ actions for coupling. The invention is, however, not restricted in this particular field of use in a 15 pipe organ. Among the objects of the invention are the provision of a structure which is positive and certain in action. There are in use appliances of this character which possess certain objections, one being 20 that the action of dust and dirt upon the same seriously affects their proper functioning. Another objection to existing structures is the fact that the material of which certain of the parts are made, is affected 25 seriously by atmospheric conditions. We provide an arrangement by which these difficulties are eliminated.

In the drawings accompanying and forming part of the present specification we have 30 shown in detail a form of embodiment of the invention which to enable those skilled in the art to practise the same will be set forth fully in the following description. We are not necessarily restricted to this disclosure; 35 we may depart therefrom in several respects within the scope of the invention defined by the claims following said description.

Referring to said drawings:

Figure 1 is a top plan view of mechanism 40 involving the invention.

Fig. 2 is a sectional side elevation of the same.

Fig. 3 is a transverse section on the line 3—3 of Fig. 2 looking in the direction of 45 the arrow.

Fig. 4 is a sectional elevation of an upright and its adjuncts.

Fig. 5 is a transverse section on the line 5—5 of Fig. 2 looking in the direction of the 50 arrow.

Like characters refer to like parts throughout the several views.

The various parts may be sustained in any desirable manner as by the base or bed 2 55 from one end of which rises the cross-piece 3, these parts being generally made of wood.

The base or bed 2 supports on the upper side thereof the uprights or wall members 4 of which there may be any convenient number. These uprights or wall members 4 are 60 generally made of wood, are spaced apart as shown, and extend from side to side of the base or bed 2. As shown their upper ends are a short distance above the upper surface of the cross-piece 3.

Certain of these uprights or wall members 4 constitute a convenient means for carrying plates as 5. As illustrated alternate uprights or wall members sustain the plates. The latter are shown as fitted closely in kerfs 65 as 6 in the upper edges of their supporting wall members. Obviously the plates 5 may be made of any desirable material, sheet brass serving our purpose in this respect. While under ordinary circumstances the fit 70 of the plates or strips 5 in their kerfs would maintain them in proper position against movement, we prefer not to rely upon this but to provide a more positive means for the purpose, the pin or locker 7 being shown for 75 this purpose. Said pin or locker extends through perforations in the upper portion of all the uprights or wall members 4 and in addition extends through registering perforations in the butt portions of the respective 80 plates or strips 5. The pin 7 in addition to 85 acting as a locker also constitutes an electrical conductor as will be hereinafter explained.

The plates 5 also support conductors as 8 90 which are usually made of wire and the ends of which extend outward beyond the terminal plates. Said conductors or wires 8 in the present case are mounted for rocking movement or oscillation. Each plate 5 as 95 shown has a row of spaced T slots 9. The journal portions of the respective conductors or wires 8 are supported for turning movement in the lower or shank portions of the respective T slots. The slots of the plates 100 are disposed in rows or groups. These wires 8 are held down in the respective shank portions of the T slots in some convenient way as by strips 10 usually of some non-conducting material as wood. Each of the 105 conductors or wires 8 has crank portions 11 between the respective plates 5.

The forward ends of the wires 8 are supported by spaced brackets 12 and 13 suitably fastened to a plate 14 in turn properly 110 attached to the upper side of the cross-piece 3, screws being generally provided to thus

mount these parts. As shown the forward ends of the wires 8 terminate in eccentric hooks 15 to which are connected the upper ends of coiled springs 16 connected at their lower ends to pins as 17 which extend outwardly from the cross-piece 3. The springs function to maintain the wires 8 and hence the cranks 11 in their off positions as shown for example by the three lower wires in Fig. 1. We will hereinafter describe a way for effecting the movement of these wires to secure a desired result.

The base or bed 2 as shown supports contacts as 18. The upper ends of these contacts are adapted to be engaged by the crank portions 11 of the wires 8 when the latter are turned from their normal positions. From the groups of contacts 18 there extend wires as 19, 20, 21, 22 and 23 connected respectively to the appropriate terminals of solenoids as 24, 25, 26, 27 and 28. The inner terminals of the solenoids are connected by a wire 29 to one pole of a generator as the battery 30, the other pole being as shown, connected by a wire as 31 with the conductor or pin 7.

It will be supposed that a wire or conductor as 8 is rocked from its open to its circuit-closing position. The two wires on the left and the one on the right in Fig. 3 are shown as occupying their normal positions, the other two being illustrated in their shifted or circuit closing positions. When the two wires are thus shifted their cranks 11 engage the upper resilient ends of contacts 18 and thus cause several of the solenoids to be energized. When the solenoids are thus energized they attract their armatures 32 to effect coupling. Usually of course it will be clear that when the circuits are closed in the manner noted, the current flows through several plates 5 by way of the pin or locker 7.

The plate 14 constitutes a suitable support for electromagnets 33 of which there may be any convenient number there being a magnet for each conductor or wire 8. The magnets are supported as shown by the plate 14 which is perforated to receive the branches of the respective magnets which as shown are of horse-shoe type. The armatures for the magnets are designated by 34 and are rigid with outer ends of the conductors or wires 8. I have not deemed it necessary to show all the connections by which the electric magnets 33 are energized, the invention not concerning this point. The connections however, are partly illustrated and include a supply wire as 35 which extends between and rests against the butt portions of sides of arms as 36 and 37 of con-

ducting material and wired as at 38 to the respective electromagnets.

Generally speaking the structure presented herein is of the same general character as that shown in Letters Patent, No. 1,113,861 granted to J. T. Austin for key mechanism for organs on October 13, 1914.

What we claim is:

1. The combination of a series of spaced uprights, plates supported by the respective uprights and each having a series of slots, cranked elements of conducting material, extending through and turning in the slots of the respective plates, and non-conducting strips in the slots, holding down the respective cranked elements. 70

2. The combination of a series of spaced uprights having kerfs, plates set in said kerfs and each having a series of slots, 80 cranked elements of conducting material extending through and turning in the slots of the respective plates, and non-conducting strips in the slots, holding down the respective elements. 85

3. The combination of a series of spaced uprights having kerfs, plates set in said kerfs and each having a series of slots, rods of conducting material extending through the uprights and the plates to hold the plates in the kerfs, cranked elements of conducting material, extending through the slots of the respective plates, and non-conducting strips in the slots, holding down the respective elements. 90

4. The combination of a series of spaced plates each having a series of slots, cranked elements extending through and turning in the slots of the respective plates, and non-conducting strips in the slots, holding down the respective cranked elements. 100

5. The combination of a series of spaced plates each having a series of T-slots, cranked elements of conducting material extending through and turning in the shank 105 portions of the respective slots, and non-conducting strips in the head portions of the slots, holding down the respective cranked elements.

6. The combination of a series of rocking 110 conductors, and magnets and their armatures, the armatures of the magnets being eccentrically connected with the respective conductors.

In testimony whereof we affix our signatures in the presence of two witnesses.

JOHN T. AUSTIN.
BASIL G. AUSTIN.
